UNITED STATES PATENT OFFICE.

HERBERT H. DOW, OF MIDLAND, MICHIGAN, ASSIGNOR TO THE DOW CHEMICAL COMPANY, OF MIDLAND, MICHIGAN, A CORPORATION OF MICHIGAN.

BLANKETING MEDIUM FOR CHEMICAL FUSIONS AND METHOD OF MAKING SAME.

1,411,421.

Specification of Letters Patent.

Patented Apr. 4, 1922.

Original application filed August 31, 1918, Serial No. 252,225. Divided and this application filed February 19, 1919. Serial No. 278,090.

To all whom it may concern:

Be it known that I, HERBERT H. Dow, a citizen of the United States, and a resident of Midland, county of Midland, and State of Michigan, have invented a new and useful Improvement in Blanketing Media for Chemical Fusions and Methods of Making Same, of which the following is a specification, the principle of the invention being herein explained and the best mode in which I have contemplated applying that principle, so as to distinguish it from other inventions.

There are many fusion processes in which the mixture of materials, upon being heated together in order to cause their interfusion, develop a tendency to oxidize excessively when exposed to the oxygen in the atmosphere. This is particularly true of fusion processes having to do with the preparation of organic compounds, such as fusions in caustic soda, or other alkali metal hydrate. It has accordingly been found advisable to blanket the fusion mixture with a suitable gas or vapor in order to protect such mass from oxidation, and I have found that for this purpose a sufficiently heavy hydrocarbon vapor, for instance gasoline vapor, is very satisfactory. However, the fusion kettles require of course to be vented, and, as might be expected, it has been found that the hydrocarbon vapor, upon being mixed with air, is very apt to form an explosive mixture. The present invention, accordingly, has as its object the provision of a suitable blanketing medium for chemical fusions, together with a method of making the same, it being noted that the present case is a division of applicant's co-pending application filed August 31, 1918, Serial No. 252,225, for improvements in fusion processes (since issued into Patent No. 1,379,619, dated May 31, 1921).

To the accomplishment of the foregoing and related ends, the invention, then, consists of the novel blanketing medium and steps for making same hereinafter fully described and particularly pointed out in the claims, the annexed drawing and the following description setting forth in detail one approved mode for carrying out the invention, such disclosed mode, however, constituting but one of the various ways in

which the principle of the invention may be used.

In said annexed drawing, the single figure there appearing illustrates in diagrammatic fashion an arrangement of apparatus for carrying out my present improved process.

Nitrogen alone, if pure, i. e. unmixed with oxygen, would of course be best suited to blanket the fusion mixture, but is not cheap enough as ordinarily made, to be available for commercial use. I have found, however, that while ordinary stack gases contain a small percentage of oxygen sufficient to cause some oxidation, if admitted directly over the fused mass, such oxygen content is so small that the formation of an explosive mixture between the same and a hydrocarbon vapor, such as hereinbefore referred to, is practically impossible.

In the drawing, a fusion pot 1 of typical form is shown seated in a suitable furnace chamber 2, whereby heat may be applied to the bottom and sides thereof so that the contents 3 of the pot may be brought to the desired temperature. The contents of the pot are sealed against contact with the outer atmosphere by a close fitting cover 4, from the center of which leads a duct 5 connected at its outer end with a larger duct, or rather flue, 6, through which stack gases from any available source are conducted. These stack gases, before reaching the point of connection of said duct therewith, will ordinarily be desirably brought in contact with a suitable reagent capable of absorbing carbon dioxide, such for example as magnesium hydrate, so as to eliminate from such stack gases the carbon dioxide present. In this way a valuable by-product in the form of magnesium carbonate is produced, and the residue is practically pure nitrogen, with only a small admixture of oxygen.

If desired, this residual gas may be utilized to directly blanket the fusion mixture in the pot, but in most cases a neutral hydrocarbon vapor, such as gasoline vapor, is preferably introduced into the pot to immediately cover the fusion mixture. Such introduction is conveniently effected by simply dripping in a quantity of liquid gasoline, which of course immediately vaporizes. In any event, it is necessary to provide a vent for the excess vapor that may be

formed, and the duct 5 accordingly serves this purpose, any excess of vapor being expelled into the larger flue 6 through which the stack gases pass; or, in the event of a reflux of the vapor into the pot, the stack gases will not form an explosive mixture with the hydrocarbon. However, the amount of oxygen in the mixture will be reduced to quite an inconsequential percentage, so no harm results from contact between the same and the mixture.

Other modes of applying the principle of my invention may be employed instead of the one explained, change being made as regards the composition and method herein disclosed provided the ingredients or steps stated by any of the following claims or the equivalent of such stated ingredients or steps be employed.

I therefore particularly point out and distinctly claim as my invention:—

1. The method of making a neutral

blanketing medium for a chemical fusion which consists in preliminarily treating flue gases to remove the carbon dioxide and then 25 adding the resultant gases to a hydrocarbon vapor to form the blanketing medium.

2. The method of making a neutral blanketing medium for a chemical fusion which consists in preliminarily treating 30 flue gases by passing same over magnesium hydrate whereby the carbon dioxide therein is absorbed with the formation of magnesium carbonate resulting in a practically pure nitrogen residuum, and then adding 35 such residuum to a hydrocarbon vapor to form the blanketing medium.

3. A blanketing medium for chemical fusions and the like consisting of flue gases from which the carbon dioxide has been removed, and hydrocarbon vapor.

Signed by me, this 15th day of February, 1919.

HERBERT H. DOW.
